(57) **CLAIM**

The ornamental design for an air conditioner, as shown and described.

DESCRIPTION

FIG. 1. is a perspective view of an air conditioner showing our new design;

FIG. 2. is a front view thereof;

FIG. 3. is a rear view thereof;

FIG. 4. is a top plan view thereof;

FIG. 5. is a bottom view thereof;

FIG. 6. is a right side view thereof;

FIG. 7. is a left side view thereof; and,

FIG. 8. is an enlarged cross-sectional view at 8-8 of FIG. 4 thereof.

The broken lines shown represent portions of the air conditioner and form no part of the claimed design.
